(57) **CLAIM**

The ornamental design for a therapeutic ice bath apparatus as shown and described.

DESCRIPTION

FIG. 1 is a front perspective view of a therapeutic ice bath apparatus showing a new design with a lid engaged; FIG. 2 is another front perspective view thereof with the lid disengaged;

FIG. 3 is a top view thereof;

FIG. 4 is a front view thereof;

FIG. 5 is a right view thereof;

FIG. 6 is back view thereof;

FIG. 7 is a left view thereof; and,

FIG. 8 is a bottom view thereof.

The broken lines in the drawing figures show portions of the therapeutic ice bath apparatus which form no part of the claimed design.

The shade lines in the figures show contour and not surface ornamentation.

1 Claim, 8 Drawing Sheets
